INVENTOR

BY Victor J. Evans

ATTORNEY

UNITED STATES PATENT OFFICE.

MARGARET B. SYLVA, OF SPRINGFIELD, ILLINOIS.

HAIR WAVER.

Application filed February 13, 1925. Serial No. 8,982.

To all whom it may concern:

Be it known that I, MARGARET B. SYLVA, a citizen of the United States, residing at 711 S. 8th St., Springfield, in the county of Sangamon and State of Illinois, have invented new and useful Improvements in Hair Wavers, of which the following is a specification.

This invention relates to new and useful improvements in hair wavers and more particularly to a device of this character which is especially adapted for use in hair-dressing whereby the same may be applied to the hair for imparting a wavy effect thereto.

10 The main object of my invention is the provision of a hair waver which is so constructed that the same may be quickly and readily applied to the hair and after being retained in engagement with the hair a predetermined length of time it will impart a wavy effect to the hair.

Another object of my invention is the provision of a hair waving article which after being applied to the hair a predetermined length of time, is removed, leaving the hair a wavy effect, and during the application of the article, the construction is such that the waves will have their ends alternately disposed and the waves will also be disposed in opposite directions laterally.

A further object of my invention is the provision of a hair waver which includes in its construction a body member having a plurality of parallel slots with arcuately-shaped cross-members between the slots and the ends of the slots extending at an angle to the main portion of the slots whereby the hair is drawn through the slots and brought tightly into contact with the arcuate surfaces and retained in a comparatively tight position so that after the article has been removed from the hair, at the termination of a predetermined length of time, a wavy effect will be imparted to the hair.

45 With the above and other objects in view, my invention consists in the novel features of construction and the combination and arrangement of parts to be hereinafter more fully described, pointed out in the claims and shown in the accompanying drawings, in which:

Fig. 1 is a perspective view illustrating the application of my invention,

50 Fig. 2 is a bottom plan view of the article,

Fig. 3 is an edge elevation,

Fig. 4 is a section on the line 4—4 of Figure 2,

Fig. 5 is a section on the line 5—5 of Figure 2,

Fig. 6 is a section on the line 6—6 of Figure 2, and

Fig. 7 is a detail perspective view of strands of hair, illustrating the effect produced by my improved waver.

In carrying out my invention, I provide a longitudinally curved body portion 1, the ends of which are slightly recessed to form the ears 2 upon each side of the body at the ends and the body is further provided with longitudinal slots 3 arranged in equal spaced relation, as clearly illustrated in Figure 2. The ends of the slots 3 are angularly disposed as shown at 4, the angularly disposed ends at one end of the slots being arranged 75 in divergent relation, as shown at 5, said divergent ends being arranged in pairs so that the ends of adjacent pairs will be disposed in convergent relation, as shown at 6.

The material between the slots forms a bearing surface 7 extending transversely of the body 1, and this bearing surface is preferably arcuate in cross-section, as is illustrated in Figure 6 with each bearing surface tapering from one end to the other as shown 80 in Figure 4, the bearing surfaces of alternate members between the slots extending in opposite directions transversely of the body and having at their inner ends divergently tapered shoulders 8 against which the 90 strands of hair engage so as to cause the same to be guided into the slots 6. Thus the cross-piece or bearing surfaces 7 which are arcuate in cross-section are tapered longitudinally of their lengths and terminate in 95 a substantially pointed portion 9, said pointed portion being disposed between the convergent angular end portions 4 of the slots 3 while the inner or thicker end portions of the bearing members 7 are disposed 100 between the divergent end portions 5 of the angular ends 4 of the slots. From this arrangement it will be apparent that when the hair is drawn through the slots 3 against the arcuate bearing surfaces 7, a portion of 105 the hair will extend into the angular end portions of the slots so that after the device has been removed, the hair will be shaped in the wavy effect illustrated in Figure 7,

wherein it will be noted that the wave portion 10 is produced through the engagement of the hair with the arcuate bearing surface

7 while the upper wave portions 11 are produced through the engagement of the transverse removable retaining bars 12. The bars 12 are engaged with a portion of the 5 hair which is drawn upwardly through the slots 3, as illustrated in Figure 6. The ends of the bars rest in the recesses 13 formed at each end of the slots 3 and the bars are preferably triangular in cross-section, as illustrated in Figure 6 whereby to provide 10 the ridge effects 14 upon each side of the upper wave portions 11.

From the above it will be apparent that 15 in using my device, the longitudinally curved body member 1 is placed upon the hair, as illustrated in Figure 1, and portions of the hair drawn upwardly through the slots 3 by the use of the bars 12, the ends of the bars being disposed in the recesses 13 20 to prevent movement thereof while the hair is being retained in position. It will be apparent from the foregoing that when the bars 12 are engaged with the hair and positioned within the slot so that their ends rest 25 in the recesses 13, the hair is drawn tightly thereover in order to retain the bars in position as is illustrated in Figs. 1 and 6. Attention is called to the fact that at each 30 end of the body, I provide the triangular-shaped strips 15, which assist in holding the hair in proper position within the innermost slots. It will be understood that prior to placing the hair within the slots and bringing the same into tight engagement 35 with the bar members 7, the hair should be slightly damped and allowed to remain in the waver until the same is comparatively dry, thus causing the hair to assume the wavy effect illustrated in Figure 7.

40 While I have shown and described the preferred form of my invention, it will be obvious that various changes in the details of construction and in the proportions may be resorted to for successfully carrying my 45 invention into practice without sacrificing any of the novel features or departing from the scope of the appended claims.

Having thus described my invention, what I claim is:

50 1. A hair waver, a body portion having parallel slots therein, said slots having angular end portions and arcuate bearing surfaces between said slots and removable bars adapted to be positioned within said slots.

55 2. A hair waver including a longitudinally curved body portion having transverse slots arranged in parallel relation, the ends of said slots extending at an angle, said angular ends being arranged in divergent

60 and convergent pairs upon opposite sides of the body and arcuate bearing surfaces

between the slots upon one side of the body and removable bars adapted to be positioned within said slots.

3. In combination with a curved body 65 having parallel slots therein, the ends of said slots extending in angular relation to the slots and the body being provided with recesses at the ends of the slots, supporting bars having their ends removably arranged 70 in said recesses and disposed within said slots.

4. The combination with a longitudinally curved body having parallel slots therein and recesses in the body at each end of the 75 slots, of supporting bars having their ends removably arranged in said recesses and disposed within said slots.

5. A hair waver including a body portion 80 having parallel slots therein, the ends of said slots extending at an angle with respect to the body portion of the slots, arcuate bearing surfaces between said slots, said bearing surfaces being tapered and alternate bearing surfaces tapering in opposite 85 directions and removable bars adapted to be positioned within said slots as their ends cooperate with the body for retaining said bars against lateral movement.

6. A hair waver including a longitudinally curved body portion having transverse parallel slots, the ends of the slots extending at an angle to the body portion, said angular ends being arranged in convergent and divergent pairs, arcuate bearing surfaces between said slots, said bearing surfaces being tapered alternately in opposite directions, divergent shoulders at the inner ends of the tapered portions and removable bars adapted to be positioned within said slots with 100 their ends cooperating with the body at the ends of the slots for retaining said bars against lateral movements.

7. A hair waver including a longitudinally curved body having transverse parallel slots therein with angular end portions, triangular-shaped strips attached to one side of the body adjacent one end and arranged parallel with the endmost slots, arcuate bearing surfaces between said slots, 105 said bearing surfaces being alternately tapered in opposite directions, divergent shoulders at the inner ends of the tapered portions and removable bars adapted to be positioned within said slots with their ends 110 cooperating with the body at the ends of the slots for retaining said bars against lateral movement.

In testimony whereof, I affix my signature.

MARGARET B. SYLVA.
